SPARK PLUG

Hector Rabezzana, Flint, Mich., assignor to General Motors Corporation, Detroit, Mich., a corporation of Delaware

Application June 6, 1938, Serial No. 211,998

10 Claims. (Cl. 123—169)

My invention relates to spark plugs comprising a hollow shell or casing threaded to screw into an opening in an internal combustion engine cylinder, an insulating member within said shell, and electrodes one carried by said insulating member and the other by said shell, said insulating member being permanently held in place within said shell which, in addition to housing said member, serves as a support for suitable means for connecting a supply conductor to the plug so as to supply current thereto; and the objects of my invention are to provide a spark plug having the features enumerated and wherein a more perfect gas tight joint is secured between the insulating member and the shell than has heretofore been the case, to provide an improved grounded or shell electrode, and to provide such other improvements in spark plugs as are hereinafter described.

In the preferred form of my invention illustrated and described the connecting means includes a metallic tube to which a braided wire covering or equivalent metallic shield upon the supply conductor may be connected, whereby a shielded system is provided to prevent the high tension current supplied to the plug from interfering with adjacent radio receiving apparatus; which is of great importance when the plugs are used in engines used to propel airplanes. The shell, the insulator, the electrodes and the means for holding the insulator permanently assembled within the shell, however, provide a spark plug assembly which is complete in itself and capable of use with connecting means other than the particular means illustrated, which in addition to its connecting function provides radio shielding for the supply conductor.

The drawing accompanying and forming a part of this specification illustrates the preferred form of my invention, although the same may be embodied in other specific forms and my invention is regarded as including such modifications and variations of the particular form illustrated and hereinafter described as come within the scope of the concluding claims.

In the drawing:

Figure 1 is a view showing a section of my proved spark plug in connection with supply conductor connecting means which provides radio shielding for the purpose stated.

Figure 2 is a view showing a section upon a transverse plane indicated by the line 2—2, Figure 1.

Figure 3 is a view showing the lower end of the

plug from a position beneath the same, looking up.

Figure 4 is a view showing my improved spark plug used with supply conductor connecting means different from the form shown in Figure 1.

Referring now to the drawing, the numeral 6 designates a hollow spark plug shell or casing made, ordinarily, from bar steel stock, and the lower end of which is externally threaded to screw into a threaded opening in an internal combustion engine cylinder. This shell has an internal ledge 7 which supports the insulating member of the plug to which end said member is provided with a lower shoulder 8 disposed above said ledge, a packing gasket 9 being commonly interposed between the shoulder and ledges as shown. The insulating member shown is made of porcelain or equivalent ceramic material having the heat resisting and other properties requisite in spark plugs; and the central insulated electrode 10 of the plug extends through a passage therein and terminates within an opening in the grounded or shell electrode of the plug. The upper end of the electrode 10 is shown as connected to a metallic washer 11 which rests upon the upper end of the insulating member, the extremity of the electrode extending through a hole in the washer and being riveted over or staked in place to fasten the parts together. The upper end of the insulating member extends above or beyond the upper end of the shell as shown.

The upper end 12 of the shell 6 is shown as hexagonal in form to receive a suitable wrench, and this upper end is internally threaded as at 13; and the insulating member includes a central portion 14 the diameter of which is slightly less than the internal diameter of the shell 6 whereby an upper shoulder 15 is provided. The end parts of the insulator below and above the shoulders 7 and 15 are of lesser diameter than the enlarged central portion thereof as shown.

Surrounding the insulating member and contacting with the upper shoulder 15 thereof is an annular holding member 16 which is C-shaped in cross section, and is made of spring steel or equivalent material; whereby a slightly yieldable member in the general form of a gasket is provided which, because of its C-shaped form, is extremely stiff and serves to maintain gas tightness between the lower shoulder 8, the gasket 9 and the supporting ledge 7 in the completed plug. That is, while in the completed plug the member 16 is forced into firm engagement with

the upper shoulder 15, leakage of gas through the shell is prevented mainly if not wholly by the gasket 9 at the lower end of the insulating member.

- 5 The C-shaped member 16 is held in place by an annular sleeve 17 the exterior of which is threaded and engages the internal threaded part 12 of the upper end of the shell, and the lower end of which fits within an annular recess 18 formed in the shell or casing 5 and engages the upper end of said member as shown. This sleeve is shorter than the internally threaded upper end of the shell so that said upper end extends above the upper end of the sleeve, and the interior of said sleeve is shown as tapered so that it may be screwed into firm contact with upper end of the member 16 by a driver having a correspondingly shaped end, to thereby force said member into firm engagement with the shoulder 15. This method of assembly stresses the holding member 16 and results in that the lower shoulder 8 is held in engagement with the gasket 9 by the resilient action of said holding member in the completed plug.
- 25 In assembling the parts thus far enumerated the insulating member is placed upon the lower gasket 9, the C-shaped holding member 16 is put in place, and the sleeve 17 is screwed into firm contact with the upper end of the member 16 with sufficient force to stress or load said member, whereby the insulating member is forced against the lower gasket 9 by the resilient action of said holding member. This holds the parts in permanently assembled relation to one another and provides a plug which will ordinarily be sufficiently gas tight when used in engines wherein the pressure within the engine cylinder is not excessive.

In order, however, to secure more perfect gas tightness when the plug is used under such high temperature and high pressure conditions as are met with in airplane service the upper end of the shell or casing is provided with a circumferentially extending groove whereby the wall thereof is reduced in thickness, as shown at 19; and, after the parts have been assembled as above explained, said thin wall section is collapsed slightly, thereby securing increased tightness at the lower gasket 9. This collapsing of the thin wall section is preferably accomplished by heating said section by a current of electricity caused to flow therethrough by contacts of a suitable electric welding or riveting device which engage the upper and lower parts of the plug. Then and while the wall section 19 is plastic, due to the heating thereof, pressure (by and through the contacts) is applied thereto, whereby more perfect joints are secured between the C-shaped member 16 and the upper shoulder 15, and between the lower shoulder 8 and gasket 9 and the ledge 7. The pressure is maintained until the thin wall section becomes cool and said section as it contracts acts further to produce gas tight joints between the shell or casing 5 and the insulating member of the plug.

The spark plug herein described is especially adapted to be used with other elements to provide a shielded spark plug, designed for use in airplane engines to prevent the high tension current supplied to the plugs from interfering with the operation of adjacent radio receiving apparatus; and my invention regarded in its more specific aspect includes a metallic shield tube 20 made, preferably, of stainless steel, and the lower end 21 of which is threaded and screws into the

upper end of the internally threaded part 12 of the shell of the plug. This shield tube has a lining 22 of insulating material such, for example, as Bakelite, and the same may be moulded inside the tube so as to be in effect integral therewith, or it may be formed as an element separable from the tube and of such shape as to fit closely therein. Whichever way it is formed the lower end 23 thereof extends beyond the lower end of the shield tube 20 and into the annular sleeve 17 as shown.

Current is supplied to the central electrode 10 through a supply cable having a conductor 23, and an insulating covering of rubber or equivalent material 24. The cable has an external metallic sheath such as braided wire covering, a flexible metal tube, or equivalent device; and this sheath is electrically connected to the shield tube 20 by a suitable coupling which engages a threaded portion 25 at the upper end thereof. The end of the cable inside the lining 22 is shown as surrounded by a sleeve 26 of insulating material such as Bakelite, and an electrical connection between the conducting wire 23 and the washer 11 and central electrode 10 is provided by a metallic spring 27. These parts for connecting the supply cable to the central electrode of the plug, and for connecting a sheath thereof to the shield tube 20 to accomplish grounding of the shield to the shell 6 of the plug, however, form no part of the invention to which this present application relates, and the showing of these parts is a conventional showing to explain the relation of the plug parts to other elements of the ignition system of an engine.

It will be appreciated that the shell or casing 5, the insulating member within the same, the annular sleeve 17 and the C-shaped member 16 whereby the insulating member is permanently held in assembled relation to the shell, together with the electrodes, provided a unitary spark plug assembly separate from the means (the shield tube 20 in the device herein described) carried by the shell for connecting the supply conductor to the plug; and that the shield tube 20 while it is claimed in some of the claims in combination with spark plug features is an element separate from the plug per se, and is in effect a part of the usual "harness" whereby a current supply conductor is connected to the plug so as to supply current to the insulated electrode thereof. The plug itself is therefore an assemblage separate from the shield tube, the insulating lining 22 therefor and other parts of the ignition harness proper, and may be used with other means carried by the shell for connecting the supply conductor to the central electrode, but which other connecting means do not provide radio shielding for supply conductor.

The grounded or shell electrode 27 is in the form of a transverse bar both ends of which are welded to the inner extremity of the shell 6 thereby providing large areas of contact between the electrode and the shell. This electrode has a central circular opening 28 into which the lower end of the central electrode 10 extends, and slots 29, 30 extend from said opening outwardly and toward the periphery of the shell. The purpose of these features is to provide for convenient adjustment of the spark gap as it will be appreciated that if the gap becomes too long, due to wear of the end of the central electrode and the wall of the opening into which it extends, the length thereof may be reduced by forcing the sides provided by the central opening and slots toward

one another as by a suitable tool of the pliers type. If in doing this the gap is made too short it may be lengthened as may be necessary by prying the sides apart by a screw driver inserted 5 into the slots.

Figure 4 shows my improved spark plug used with connecting means carried by the shell or casing for connecting a supply conductor to the plug, but in which radio shielding is not present. 10 In said figure the shell, the insulating member, and the means for holding said member permanently assembled within the shell are the same as shown in Figure 1 and hereinbefore described; but in this figure the cap 31 which encloses the 15 upper end of the insulating member, and which screws into the upper internally threaded part 12 of the shell, is made of an insulating material such as Bakelite and carries a terminal post 32 to which a supply conductor may be connected by 20 a suitable connector, a conducting path to the central electrode being provided by a spring 33 corresponding with the spring 21 in the form of my invention illustrated in Figure 1.

Having thus described and explained my invention I claim and desire to secure by Letters Patent:

1. In a spark plug of the class described, a hollow metallic shell or casing which is externally threaded to screw into a threaded opening in an engine cylinder, and the upper end of which is internally threaded; an insulating member within said shell and having upper and lower shoulders spaced apart from one another, and the upper end of which insulating member extends above said shell; a ledge within said shell whereby said insulating member is supported; an externally threaded annular sleeve within the upper internally threaded part of said shell; an annular holding member located between the 35 lower end of said sleeve and the upper shoulder of said insulating member; a tubular metallic shield the lower end of which is threaded and screws into the threaded upper end of said shell; and a lining of insulating material within 40 said shield and surrounding the upper end of said insulating member.

2. In a spark plug of the class described, a hollow metallic shell or casing which is externally threaded to screw into a threaded opening in an engine cylinder, and the upper end of which is internally threaded; an insulating member within 45 said shell and having upper and lower shoulders spaced apart from one another, and the upper end of which insulating member extends above said shell; a ledge within said shell whereby said insulating member is supported; an externally threaded annular sleeve within the upper internally threaded part of said shell; a resilient annular metallic holding member C-shaped in cross section located between the lower end of said annular sleeve and the upper shoulder of said insulating member; a tubular metallic shield the lower end of which is threaded and screws into the threaded upper end of said shell; and a lining of insulating material within 55 said shell and surrounding the upper end of said insulating member, and the lower end of which lining extends beyond said shield and into said annular sleeve.

3. In a spark plug of the class described, a hollow metallic shell or casing having an externally threaded part at its lower end to screw into a threaded opening in an engine cylinder, and the upper end of which is internally threaded 75

and has an external circumferentially extending groove, and an internal annular recess; an insulating member within said shell and having lower and upper shoulders spaced apart from one another, and the upper end of which insulating member extends above said shell; a ledge within said shell whereby said insulating member is supported; an externally threaded annular sleeve within the upper internally threaded part of said shell, and the lower end of which extends into the annular recess aforesaid; and an annular holding member located between the lower end of said sleeve and the upper shoulder of said insulating member. 5

4. In a spark plug of the class described, a hollow metallic shell or casing having an externally threaded part at its lower end to screw into a threaded opening in an engine cylinder, and the upper end of which is internally threaded and has an external circumferentially extending groove, and an internal annular recess; an insulating member within said shell and having lower and upper shoulders spaced apart from one another, and the upper end of which insulating member extends above said shell; a ledge within 10 said shell whereby said insulating member is supported; an externally threaded annular sleeve within the upper internally threaded part of said shell, and the lower end of which extends into the annular recess aforesaid; and an annular holding member located between the lower end of said sleeve and the upper shoulder of said insulating member. 15

5. In a spark plug of the class described, a hollow metallic shell or casing having an externally threaded part at its lower end to screw into a threaded opening in an engine cylinder, and the upper end of which is internally threaded and has an external circumferentially extending groove, and an internal annular recess; an insulating member within said shell and having lower and upper shoulders spaced apart from one another, and the upper end of which insulating member extends above said shell; a ledge within 20 said shell whereby said insulating member is supported; an externally threaded annular sleeve within the upper internally threaded part of said shell, and the lower end of which extends into the annular recess aforesaid; and a resilient 25 annular metallic holding member C-shaped in cross section located between the lower end of said annular sleeve and the upper shoulder of said insulating member. 30

6. In a spark plug of the class described, a hollow metallic shell or casing having an externally threaded part at its lower end to screw into a threaded opening in an engine cylinder, and the upper end of which is internally threaded and has an external circumferentially extending groove, and an internal annular recess; an insulating member within said shell and having lower and upper shoulders spaced apart from one another, and the upper end of which insulating member extends above said shell; a ledge within 35 said shell whereby said insulating member is supported; an externally threaded annular sleeve within the upper internally threaded part of said shell, and the lower end of which extends into the annular recess aforesaid; a resilient annular metallic holding member C-shaped in cross section located between the lower end of said annular sleeve and the upper shoulder of said insulating member; a tubular metallic shield the lower end of which is threaded and screws into the threaded upper end of said shell; and a lining of insulating material within 40 said shell and surrounding the upper end of said insulating member. 45

7. In a spark plug of the class described, a hollow metallic shell or casing having an externally threaded part at its lower end to screw into a threaded opening in an engine cylinder, and the upper end of which is internally threaded and has an external circumferentially extending 50 groove, and an internal annular recess; an insulating member within said shell and having lower and upper shoulders spaced apart from one another, and the upper end of which insulating member extends above said shell; a ledge within 55 said shell whereby said insulating member is supported; an externally threaded annular sleeve within the upper internally threaded part of said shell, and the lower end of which extends into the annular recess aforesaid; a resilient annular 60

metallic holding member C-shaped in cross section located between the lower end of said annular sleeve and the upper shoulder of said insulating member; and a metallic shield the lower end 5 of which is threaded and screws into the threaded upper end of said shell.

7. In a spark plug of the class described, a hollow metallic shell or casing having an externally threaded part at its lower end to screw 10 into a threaded opening in an engine cylinder, and the upper end of which is internally threaded and has an external circumferentially extending groove whereby a shell wall thickness of reduced area is provided at the bottom of 15 said groove, and which shell has an internal annular recess below said groove; an insulating member within said shell and having lower and upper shoulders spaced apart from one another, and the upper end of which insulating member 20 extends above said shell; a ledge within said shell whereby said insulating member is supported; an externally threaded annular sleeve within and of less length than the upper internally threaded part of said shell, and the lower end 25 of which extends into the annular recess aforesaid; and an annular holding member located between the lower end of said sleeve and the upper shoulder of said insulating member; the wall section of reduced area at the bottom of 30 said groove having been collapsed after the insulating member has been assembled within the shell and after said annular holding member has been screwed into the upper threaded part of said casing to hold said insulator in place 35 therein.

8. In a spark plug of the class described, a hollow metallic shell or casing having an externally threaded part at its lower end to screw into a threaded opening in an engine cylinder, and 40 the upper end of which is internally threaded and has an external circumferentially extending groove whereby a shell wall thickness of reduced area is provided at the bottom of said groove; an insulating member within said shell and having lower and upper shoulders spaced apart from one another, and the upper end of which insulating member 45 extends above said shell; a ledge within said shell whereby said insulating member is supported; an externally threaded annular sleeve within and of less length than the upper internally threaded part of said shell; and an annular holding member located between the lower end of said sleeve and the upper shoulder of said insulating member; the wall section 50 of reduced area at the bottom of said groove having been collapsed after the insulating member has been assembled within the shell and after said annular holding member has been screwed

into the upper threaded part of said casing to hold said insulator in place therein.

9. In a spark plug of the class described, a hollow metallic shell or casing having an externally threaded part at its lower end to screw into a 5 threaded opening in an engine cylinder, and the upper end of which is internally threaded and has an external circumferentially extending groove whereby a shell wall thickness of reduced area is provided at the bottom of said groove, 10 and which shell has an internal annular recess below said groove; an insulating member within said shell and having lower and upper shoulders spaced apart from one another, and the upper end of which insulating member extends above 15 said shell; a ledge within said shell whereby said insulating member is supported; an externally threaded annular sleeve within and of less length than the upper internally threaded part of said shell; and the lower end of which extends into 20 the annular recess aforesaid; and a resilient annular metallic holding member C-shaped in cross-section located between the lower end of 25 said sleeve and the upper shoulder of said insulating member; the wall section of reduced area at the bottom of said groove having been collapsed after the insulating member has been assembled within the shell and after said annular holding member has been screwed into the 30 upper threaded part of said casing to hold said insulator in place therein.

10. In a spark plug of the class described, a hollow metallic shell or casing having an externally threaded part at its lower end to screw into a threaded opening in an engine cylinder, 35 and the upper end of which is internally threaded and has an external circumferentially extending groove whereby a shell wall thickness of reduced area is provided at the bottom of said groove; an insulating member within said shell 40 and having lower and upper shoulders spaced apart from one another, and the upper end of which insulating member extends above said shell; a ledge within said shell whereby said insulating member is supported; an externally threaded annular sleeve within and of less length than the upper internally threaded part of said shell; and a resilient annular metallic holding member 45 C-shaped in cross-section located between the lower end of said sleeve and the upper shoulder of said insulating member; the wall section of reduced area at the bottom of said groove having been collapsed after the insulating member has been assembled within the shell and after said annular holding member has 50 been screwed into the upper threaded part of said casing to hold said insulator in place therein.

HECTOR RABEZZANA.
